ADJUSTABLE FOOT MECHANISM FOR SASH BALANCES

William E. Gency, Old Greenwich, Conn., assignor to Unique Balance Co., Inc., New York, N. Y., a corporation of Illinois

Application July 7, 1955, Serial No. 520,442

11 Claims. (Cl. 16—197)

This invention relates to mechanisms by means of which the tension of the springs of spiral sash balances may be adjusted and, more particularly, to devices of such character that may be incorporated in or adjacent to the foot mechanism of the balances in order to facilitate the aforesaid adjustment.

Spiral sash balances of the general nature with which this invention is concerned are illustrated, for example, in U. S. Patent No. 1,864,745. Various mechanisms have heretofore been designed to permit of adjustment of the spring tension in these balances. These previously suggested adjusting mechanisms, however, have been inadequate to satisfy the requirements of the trade either because of the inherent difficulty of manipulating them or because the location of the mechanisms has rendered them inaccessible after the balances have been installed.

An object of the present invention, accordingly, is to provide a mechanism by means of which the spring tension of spiral sash balances of the above character may be readily adjusted after the balance has been installed.

Yet another object of the invention is to provide an adjusting mechanism of the above character which may be inexpensively manufactured and conveniently installed, the mechanism being such as to permit the manufacture of a sub-assembly which may be installed on location and connected to the spiral balance mechanism, the spring tension of which is to be controlled.

The foregoing and other objects are attained by providing an adjusting mechanism that may be incorporated in or carried by the structure of the foot plate; the mechanism being so formed as to permit of adjustment by the application of a tool such as a screw driver thereto from a position directly beneath the foot plate. Furthermore, the mechanism utilizes a ratchet and pawl connection normally biased into engaging position by a spring which is released by initial axial movement of the screw driver prior to the turning movement which effects the desired tension of the balance spring.

In order that the invention may be more readily understood, reference will now be made to the accompanying drawings, wherein:

Fig. 1 is an exploded view of an adjusting mechanism, constructed in accordance with the present invention, this view illustrating the various parts in axial alignment;

Fig. 2 is a perspective view of a conventional form of spiral sash balance and its foot plate with the adjusting mechanism of the present invention incorporated therein;

Fig. 3 is a view similar to Fig. 2 illustrating the manner in which the adjustment of the main spring of the spiral sash balance may be effected, the parts in this view being shown in a position in which they would exist at some point during the adjusting operation;

Fig. 4 is a view in horizontal section taken on the plane indicated by the line 4—4 and looking in the direction of the arrows; and

2

Fig. 5 is a view in vertical section taken on the plane indicated by the line 5—5 and looking in the direction of the arrows.

Referring to the above drawings, a conventional form of spiral sash balance is illustrated generally at 10, the balance comprising a spiral spring 11, the upper end of which is formed with an eye 12 which is adapted to be secured to the window frame and the lower end of which is formed with a nut 13 having a slot 14 formed therein. A spirally formed strip 15 is received within the slot 14 and is formed with a varying pitch, all in accordance with known practice.

In order that the spiral sash balance 10 may be effectively and conveniently secured to the window sash, a foot plate 16 is provided in accordance with common practice. The foot plate is formed with a tooth 17 that is driven into the lower edge of the sash and with a suitable number of apertures 18 to permit the plate to be secured to the bottom of the sash by means of screws.

In accordance with this invention, the tension of the spring 11 or its loading may be adjusted effectively by a mechanism comprising a plate 19 that is formed as an extension, somewhat offset, of the foot plate 16. A portion of the foot plate is pressed upwardly into a stop or locating detent 20 to facilitate the location of the foot plate upon the bottom of the window sash and to prevent the securing of the foot plate to the sash in such a position as to impair the operation of the spring adjusting mechanism presently to be described.

Upon opposite sides of the plate 19, pawl teeth 21 are formed, in the form of the invention illustrated these teeth extending upwardly and lying generally in planes that are perpendicular to the plane of the plate 19. A central aperture 22 is formed in the plate 19 and is adapted to receive oppositely spaced curved arms 23. The upper extremities of the arms 23 receive between them the lower end of the spiral member 15, a hinge pin 24 being provided to secure these elements together. The upper extremities of the arms 23 are upset or flanged over to provide inwardly extending flanges 25, these flanges serving to make captive a coil spring 26 that is received between the arms 23.

As illustrated in Figs. 1, 2, 3 and 5, the arms 23 are formed upon an adjusting plate 27, this plate being provided with a slot 28 to receive the bit of a screw driver such as is illustrated in phantom in Fig. 3 in order that the mechanism may be manipulated as will be presently described.

A ratchet plate 29 (illustrated particularly in Fig. 1) is formed with oppositely disposed notches or recesses 30 that are adapted to receive the pawls 21 and to prevent rotation of the plate 29 in one direction (counter-clockwise as viewed in Fig. 1). The plate 29 is formed with a diametrically extending bar 31 having a central enlargement 32 against which the spring 26 seats in order that the plate 29 may normally be urged downwardly and retained against the plate 19. As a result of the foregoing structure, spaced semi-circular slots 33 are formed within the plate 29 and through which the arms 23 extend when the elements are in assembled position as illustrated in Figs. 2, 3, 4 and 5.

As illustrated in Fig. 1, the parts are assembled by inserting the arms 23 through the central aperture 22 of the plate 19, placing the plate 29 in position over the plate 19 and with the arms 23 extending through the slots 33, then inserting the coil spring 26 between the arms 23 and peening or flanging over the extensions 25 into the position illustrated in Figs. 4 and 5. In this fashion, the coil spring 26 is captive and the elements including the foot plate 16 are formed as a sub-assembly. This sub-assembly may either be secured directly to the lower extremity of the spiral strip 15 at the time

the sash balance is manufactured or be secured thereto at the point of installation of the sash balance. All that is required is that the pin 24 be inserted through the apertures in the arms 23 and the aperture in the bottom of the spiral member 15 and then the straight end of the pin riveted over to secure the pin against accidental removal. In the assembled position, the lower end of the strip 15 is pressed against the coil spring 26 which in turn engages the central enlargement 32 to maintain the pawl teeth 21 in engagement with the ratchet plate 29.

Adjustment of the tension of the spring 11 is accomplished by inserting the bit of a screw driver (indicated in phantom at 34) into the slot 28. If the tension of the spring 11 is to be increased, then the screw driver need only be turned in a counter-clockwise direction as viewed from below in Fig. 3. This will cause the plate 29 to be moved in a corresponding direction and the pawl teeth 21 will move the plate upwardly to disengage the teeth from the notches 30 (turning of the plate 27 and the arms 23 causes the latter to engage the diameter bar 31 to move the plate 29). Continued rotation through 180 degrees will cause the notches to snap into position with respect to the pawl teeth 21 and thus prevent unwinding of the spring. Continued motion as above described will cause increased tensioning of the spring. If the tension of the spring is to be decreased, the screw driver is first moved axially (upwardly in Fig. 3) to cause the bit to engage the bottom of the circular plate or disc 32 and push the plate 29 upwardly until the notches 30 disengage the teeth 21. At this instant, the tension of the spring 11 will tend to cause the plate 29 to move in a clockwise direction as viewed from below in Fig. 3 (as a result of arms 23 engaging the diameter bar 31). This motion is resisted to the extent desired by the operator and sufficiently to permit gradual release of the spring tension. It will be understood, of course, that the pressure of the coil spring 26 will normally permit this releasing motion to take place in half-turn stages of the plate 29. If continued release of tension is desired, then the screw driver 34 must be urged upwardly to maintain the plate 29 and its notches 30 out of engagement with the teeth 21.

I claim:

1. An adjusting mechanism for spiral sash balances comprising a first plate carried by the foot-plate of a spiral sash balance, the first plate having a central aperture therein, an adjusting member rotatably mounted below the first plate and having an extension extending upwardly through said aperture adapted to operatively engage the sash balance, a second plate above the first plate having means to engage said extension of the adjusting member, a ratchet and pawl mechanism between the plates, means to maintain said ratchet and pawl mechanism in operative relationship, and means on said adjusting member to enable it to be turned by suitable instrument.

2. A device according to claim 1 wherein the means on the adjusting member to enable it to be turned comprises a slot formed therein through which the ratchet is accessible by said instrument, thereby to disengage said ratchet and pawl to release the tension of the spiral sash balance.

3. A device according to claim 1 wherein the means for maintaining the ratchet and pawl relationship is a spring.

4. A device according to claim 3 wherein the ratchet mechanism comprises a circular ratchet plate mounted between the first plate and the spring.

5. A device according to claim 3 wherein the extension is formed of two arms and the spring is mounted between the arms.

6. A device according to claim 5 wherein the arms are

formed with inwardly extending flanges overlying the spring to render the same captive.

7. A device according to claim 5 wherein the arms are curved to enclose said spring and the second plate is formed with a curved slot through which the arms extend.

8. An adjusting mechanism for spiral sash balances comprising a first plate carried by the foot plate of a spiral sash balance said first plate having a central aperture therein and two pawl teeth thereon, an adjusting plate 10 rotatably mounted below the first plate, a ratchet plate above the first plate having two notches forming two ratchet teeth adapted to engage said pawl teeth and having two slots therein, a spring above said ratchet plate adapted to engage said ratchet plate and thereby maintain said ratchet plate in engagement with said first plate, said adjusting plate having two arms thereon which extend through said central aperture and said slots, said arms having means whereby they may be secured to the lower end of a spiral sash balance, said adjusting plate having a slot therein to enable it to be turned.

9. An adjusting mechanism for spiral sash balances comprising a first plate carried by the foot plate of a spiral sash balance said first plate having a central aperture therein and two upstanding pawl teeth thereon, an 15 adjusting plate rotatably mounted below the first plate, a circular ratchet plate above the first plate having two notches forming two ratchet teeth adapted to engage said pawl teeth and having two curved slots defining a diameter bar and a central enlarged portion of said bar, a helical spring above said ratchet plate adapted to engage 20 said enlarged portion and thereby maintain said ratchet plate in engagement with said first plate, said adjusting plate having two arms thereon which extend through said central aperture and are curved so as to pass through 25 said slots and enclose said spring, said arms having inwardly extending flanges to maintain said spring captive and means whereby they may be secured to the lower end of a spiral sash balance, said adjusting plate having a slot therein to enable it to be turned.

10. An adjusting mechanism for spiral sash balances comprising a first plate carried by the foot-plate of a spiral sash balance the first plate having a central aperture therein and at least one pawl tooth thereon, an 45 adjusting member rotatably mounted below the first plate and having an extension extending upwardly through said aperture adapted to operatively engage the sash balance, a ratchet plate above the first plate having at least one notch forming at least one ratchet tooth adapted to engage said pawl tooth and having means to engage 50 said extension of the adjusting member, a spring above said ratchet plate adapted to engage said ratchet plate and thereby maintain said ratchet plate in engagement with said first plate, and means on said adjusting member enabling it to be turned by a suitable instrument.

11. A device according to claim 1 wherein the means on the adjusting member to enable it to be turned comprises a slot formed therein through which the second plate is accessible by said instrument so that the instrument when in operative position may separate said second plate from said first plate by counteracting the means to maintain said ratchet and pawl in operative relationship, thereby to disengage said ratchet and pawl and release the tension of the spiral sash balance.
